CLAIM

The ornamental design for a clock, as shown and described.

DESCRIPTION

FIG. 1 is a top front perspective view of a clock according to the present invention.

FIG. 2 is a bottom rear perspective view of the clock of FIG. 1.

FIG. 3 is a front view of the clock of FIG. 1.

FIG. 4 is a rear view of the clock of FIG. 1.

FIG. 5 is a first side view of the clock of FIG. 1.

FIG. 6 is a second, opposite side view of the clock of FIG. 1.

FIG. 7 is a top view of the clock of FIG. 1.

FIG. 8 is a bottom view of the clock of FIG. 1.

FIG. 9 is a rear perspective view of the clock of FIG. 1, shown in an alternative configuration.

FIG. 10 is a first side thereof.

FIG. 11 is a front view of the clock of FIG. 1, shown in a state of use.

FIG. 12 is a front view of the clock of FIG. 1, shown in an alternate state of use; and,

FIG. 13 is a front view of the clock of FIG. 1, shown in another alternate state of use.

The broken lines illustrate portions of the clock that form no part of the claimed design.

1 Claim, 13 Drawing Sheets
